TRAIN ORDER DELIVERING DEVICE

Edward Clyde Weatherly, Redfield, S. Dak.

Application January 23, 1939, Serial No. 252,285

3 Claims. (Cl. 258—2)

This invention relates to train order delivering devices.

It is the general object of this invention to provide a novel and improved train order delivering device of cheap and simple construction which can be used with safety by a station agent to deliver orders and messages to members of a train crew on a train passing a station without necessitating slowing down or stopping of the train.

Another object is to provide a train order delivering device so arranged that it can be used to deliver separate orders or messages to one, two, three, or four members of a train crew.

Another object is to provide such a device which can be quickly stowed away when not in use and can be quickly erected for use when desired.

The objects and advantages of the invention will more fully appear from the following description, made in connection with the accompanying drawings, wherein like reference characters refer to the same or similar parts throughout the various views and in which:

Fig. 1 is a view in side elevation illustrating an embodiment of the present invention erected in position on a station platform alongside of a railroad track;

Fig. 2 is a similar view in larger scale showing the upper portion of the device and illustrating certain of the parts in message delivering position in full line and in distended position in dotted line;

Fig. 3 is a horizontal section taken on the line 3—3 of Fig. 2, as indicated by the arrows, the parts being shown in still larger scale;

Fig. 4 is a vertical section taken on the line 4—4 of Fig. 3 as indicated by the arrows;

Fig. 5 is a detail showing the outer end of one of the arms of the device equipped with a cord holding spring clip;

Fig. 6 is an end view of one of the spring clips which may be employed;

Fig. 7 is a section taken on the line 7—7 of Fig. 2 as is indicated by the arrows, the view being in enlarged scale;

Fig. 8 is a detail showing the manner of attachment of the message to the cord carrying the same;

Fig. 9 is a vertical section through the standard and the upper part of the receiving tube and illustrating how the standard is retained in position on the receiving tube; and

Fig. 10 is a horizontal section taken on the line 10—10 of Fig. 9 as indicated by the arrows.

Referring to the drawings, a railroad station platform is shown in Fig. 1 and designated by the numeral 11. One of the rails 12 of the railroad track is shown as being supported by tie 13. Sunk into the ground and terminating at its upper end preferably flush with a slight mound 14, built into the platform 11, is a standard receiving tube 15, the upper end of which is equipped preferably with diametrically opposed pin receiving notches 15a, as best shown in Fig. 9. The receiving tube 15 is of such length and size as to loosely receive a vertical standard 16 which carries at its upper end a cap 17 which will close the opening in the tube 15 when the standard is dropped to its lowest position in the tube. The cap 17 is preferably provided with a ring 18 forming a finger grip which can be grasped to raise the standard 16 upwardly from the tube 15. Near the lower end of the standard 16 suitable retaining means is provided to hold the standard in raised position from the tube and to prevent unintentional rotation of the standard relative to the tube. In the illustrated embodiment, the standard 16 is of tubular construction and a small casing 19 apertured at both ends is set diametrically of the tubular standard near its lower end. Headed pins 20 are received within the casing 19 and these pins project through diametrically opposed apertures in the standard 16 and they are forced outwardly by means of a spring 21 located within the casing 19 and bearing against the heads of these pins. As the standard 16 is raised to a certain height from the tube 15, the pins 20 are forced outwardly by the spring 21 and by turning the standard 16 to the proper position, relative to tube 15, the pins 20 may be brought into registry with the notches 15a of the tube to be received within these notches. When the pins are so received the standard 16 is supported in extended position from the tube 15 and the standard cannot turn unless it is raised to carry the pins 20 out of the notches 15a.

The standard 16 is preferably provided with four pair of elongated slots 16a. One pair of these slots are located near the upper end of the standard 16 to face outwardly toward the rail 12 when the pins 20 are received within the notches 15a of the tube 15. Another pair of these slots 16a are located in spaced relation downwardly in alignment with the first pair of slots mentioned. The third pair of slots are located at the same height as the first pair, but are disposed 90° around the standard from the first pair. The fourth pair of slots 16a are in vertical alignment with the third pair but located at the same level.

as the second pair. The two slots of a pair are located in vertically spaced relation from each other to receive a pair of hooks 22 secured to brackets 23 carried by a bar 24. Each bar 24 5 on its side facing away from the side that hooks on to the standard 16, carries a pair of vertically spaced channel shaped brackets 25 to each of which the inner end of an arm 26 or 27 is pivotally connected by a pivot 28. The upper arms 10 are designated 26, and the lower arms are designated 27. Each arm 26 and 27 has swivelly connected to its outer end a spring cord retaining clip 29, each clip being mounted as on a screw or pin 30 forming a pivot and fastened in the 15 outer end of an arm 26, or 27.

In the illustrated embodiment the cord retaining spring clips 29 are shown as being merely the ordinary spring clothes pins 29, such as commonly employed on coat hangers, skirt hangers, etc. Each clip includes a pair of lever like jaws 29a and a spring 29b having a helical portion located between intermediate portions of the jaws and having end portions received in notches formed in the jaws 29a near their gripping ends. 25 The helical portion of each spring 29b forms a convenient eye to receive the pivot 30.

Upward swinging movement of each upper arm 26 is limited as by an angular bracket 31, carried by the bar 24 near its upper end.

30 Each upper arm 26 carries a depending channel bracket 32 intermediate the ends thereof and connected by a pivot 33 to each bracket 32 is a strut 34 to which a third spring clip 35 is secured intermediate the ends of the strut. The spring clip 35 employed may be variously formed but the illustrated embodiment is in the form of an ordinary paper clip of substantially U-shape, having its central portion secured to the strut as by means of a screw 36 as shown in Fig. 7 and 40 having spring arms with rounded free edges which normally contact each other, the arms also being provided with handle levers 35a for spreading apart the spring arms. The strut 34 when the delivering device is in extended position bears against a channel shaped block 37 secured to the upper side of the lower arm 27 and the strut serves to hold the two arms 26 and 27 45 apart in diverging relation. Also when the strut is located, as best shown in Fig. 2, in the position 50 it will assume when the delivering device is extended, the third clip 35 will be located about mid-way between the two spring clips 29 and in inwardly disposed relation relative to the standard 16 from the spring clips 29.

55 Each bar 24 with its parts connected thereto including an upper arm 26, a lower arm 27, the two cord holding clips 29 attached to these arms, the strut 34 connected to the upper arm 26 and the spring clip 35 attached to the strut, forms a delivery unit for use in delivering a single train order of message. This unit can be very quickly applied to or detached from the standard 16 by engaging the hooks 22 with, or disengaging the hooks 22 from, a pair of the slots 16a of the standard. The delivery unit can be readily collapsed to distended position shown in dotted lines in Fig. 2 and for the purpose of holding the parts in collapsed condition, the bar 24 is equipped with spring prong retaining devices 38 65 to catch and receive latching members 39 mounted on the lower sides of the two arms 26 and 27. Accordingly when the delivery unit is removed from the standard 16, it can be stowed away in small compass as within a railroad station. 70 Preferably a second retaining device 40 for

holding the standard 16 in partially raised position from the tube 15, is provided with the second retaining device consisting of pins, spring and casing similar to the pins 20, spring 21 and casing 19 of the retaining device heretofore described. The second retaining device 40 is preferably located about mid-way between the two ends of the standard 16.

Whenever it is desired to deliver a train order from a station agent to a moving train passing 10 the station where the station agent is located, the station agent will first select a cord 41 of the proper length to be suspended in triangular relation from one of the delivery units as indicated in Figs. 1 and 2. The two ends of the cord 41 15 are tied together by means of slip knots 42 and the train order 43 consisting of a folded paper carrying the message thereon is slipped between the two knots 42 whereupon the knots are drawn tight to securely hold the train order in position 20 attached to the cord 41. Let us assume that the station agent wishes to deliver the train order to the train engineer only. Having prepared the cord 41 with the train order 43 attached thereto, the station agent will go to the train platform 25 and grasping the ring 18, he will raise the standard 16 to a point where the upper retaining device 40 will hold the standard in partially extended condition from the receiving tube 15. The station agent will then take one of the delivery units, which may for convenience be designated by the letter A and hook this unit to the standard 16 by engaging the hooks 22 of the unit in the pair of slots 16a nearest the top of the standard and located in alinement with the pins 20. The station agent will then raise the upper arm 26 of the unit A from the dotted line position shown in Fig. 2 to the full line position there shown to bring this upper arm into engagement with the stop 31. The cord 41, at a point about opposite the train order 43, is then engaged with the cord holding spring clip 35 carried by the strut 34 whereupon other portions of the cord are engaged with the two spring clips 29 carried respectively by the upper and lower arms 26 and 27 of the unit. The cord 41 will then assume the triangular shape shown in Fig. 2, the lower end of the strut 34 being received within the channel of the block 37 and the lower arm 27 of the unit being supported from the upper arm 26 through the medium of the cord 41. Thereupon the standard 16 is raised from the receiving tube 15 to its full height causing the pins 20 of the lower retaining device to be received within the notches 15a of the tube 15 to hold the delivery unit A in such position that it will not rotate and at right angles to the track over which the train is to run. It will, of course, be understood that the unit A will then be disposed at a convenient height to be readily reached by the engineer of the train from the locomotive cab window.

As the train to receive the train order approaches the station where the present device is located, the engineer observing the device set up 65 will realize that he is to receive a train order from the station agent and without slackening the speed of the train he will, as the locomotive passes the present device, reach out with his arm through the loop of the cord 41 and snare the cord with the order 43 attached thereto on to his arm. He thus snatches the cord 41 with the train order 43 attached thereto from the delivery unit A, the cord releasing freely from the spring clip 35 and from the two spring clips 29, said 70 75

spring clips 29 swiveling on their pivots 30 to permit of ready release of the cord therefrom. As the cord is snatched from the unit A the lower arm 27 is no longer supported and therefore it falls from the full line position shown in Fig. 2, to the dotted line position there shown, thereby allowing the upper arm 26 and the strut 34 to swing downwardly from the full line position shown in Fig. 2 to the dotted line position there shown, whereupon the unit is completely collapsed.

It is usually desirable to deliver similar train orders to both the engineer and the conductor of the same train and hence provision is made on the standard 16 for accommodating a second delivery unit B directly below the delivery unit A and within the ready reach of the conductor while standing on a platform or steps of one of the cars of the train. Occasionally it will be necessary to deliver train orders to two engineers driving two locomotives on a double header train and also to the conductor of this train. Therefore, provision has been made on the standard 16 for accommodating other delivery units, such as C, set at right angles to units A and B. In making delivery of train orders to two engineers and one conductor on the same train the units A and B will be rigged as previously described and an additional unit C set at right angles to the unit A will also be rigged. As the train approaches, the engineer in the first locomotive will snatch the cord and train order from the first unit A and the conductor will snatch the cord and train order from unit B whereupon the station agent will quickly slightly raise the standard 16 to carry the pins 20 out of the notches 15a of the tube 15, and he will then turn the standard 16 to bring the other unit C normal to the track and projecting toward the track. While the station agent holds the standard 16 the engineer driving the second locomotive will snatch the train order and cord from the unit C. Of course, two units C, an upper unit and a lower unit (not illustrated) may be employed if desired for use when the two locomotives of the train are not separated by intervening cars.

The triangular stringing of the cord 41 carrying the train order 43 makes it possible for members of the train crew to pick up the cord and train order with great ease and without hazard. The spacing between the two arms 26 and 27 of this unit is such that there is very little chance for a member of the train crew to strike either one of the arms as the train order is picked up.

It will be seen that a practical, safe, simple and dependable delivery device for train order has been provided which can be set up with great ease and which will be effective for delivering an order to a fast moving train from a station platform without necessitating slowing down or stopping of the train. The device has been successfully demonstrated in actual practice.

It will, of course, be understood that various changes may be made in the form and details, arrangement and proportions of the various parts without departing from the scope of the present invention which, generally stated, consists in the matter shown and described and set forth in the appended claims.

What is claimed is:

1. A train order delivering device comprising a vertical standard, a bar releasably connected thereto, an upper arm and a lower arm pivotally connected to said bar in vertically spaced relation and projecting outwardly therefrom, a pair of cord holders releasable upon pressure applied to the cord held thereby and carried respectively by the outer ends of said arms, a stop limiting upward swinging movement of said upper arm, a strut pivotally connected to said upper arm and bearing against said lower arm, a third cord holder releasable upon pressure applied to the cord held thereby and carried by said strut, and said third cord holder being disposed inwardly from the outer ends of said arms relatively to said bar, said third cord holder being adapted to support a message carrying cord strung therefrom in triangular outline.

2. The structure defined in claim 1, a receiving tube mounted in the ground and adapted to receive said standard and means cooperating with said standard and tube to hold said standard from unintentional rotation when said standard has been raised from said tube to a certain height.

3. A train order delivering device comprising a receiving tube mounted in the ground, a standard telescopically received within said tube and extensible upwardly therefrom, means for holding said standard so extending to prevent unintentional rotation of said standard, a plurality of delivery units, each unit comprising a hook equipped bar, an upper arm and a lower arm pivotally connected at their inner ends to said bar and projecting outwardly therefrom, a pair of cord holders releasable on pressure applied to the cord held thereby and carried respectively by the ends of said arms, a stop, limiting possible upward swinging movement of the upper arm, a strut pivotally connected to the upper arm and normally bearing against the lower arm and a third cord holder releasable upon pressure applied to the cord held thereby and carried by the strut and inwardly disposed relative to the bar from said pair of cord holders, said three cord holders being adapted to support a message carrying cord strung therefrom in triangular outline, said standard including means for receiving the hooks of said bars with a pair of said units disposed in a plane at right angles to the plane in which a third unit is disposed.

EDWARD CLYDE WEATHERLY.
